(57) **CLAIM**

The ornamental design for a vehicle front door, as shown and described.

DESCRIPTION

The vehicle front door is styled independently of adjacent vehicle panels. To the extent that any feature lines are illustrated, they are intended to illustrate the crest and valley of the feature and are not necessarily sharp bends in the part. Shading is used to illustrate the curvature of the part and not color. Areas shown in or bounded by broken lines are not claimed. Any functional features of the vehicle front door are not claimed. Views are orthogonal projections unless otherwise noted. The various views are not necessarily to scale in order to better illustrate the design.

FIG. 1 is a perspective view of a right vehicle front door (the left vehicle front door being a mirror of the right and is not illustrated);

FIG. 2 is a right side elevational view of the vehicle front door;

FIG. 3 is a left side elevational view of the vehicle front door;

FIG. 4 is a top plan view of the vehicle front door;

FIG. 5 is a bottom plan view of the vehicle front door;

FIG. 6 is a front elevational view of the vehicle front door; and,

FIG. 7 is a rear elevational view of the vehicle front door.
